UNITED STATES PATENT OFFICE.

WILLIAM E. SMITH, OF MILLTOWN, NEW JERSEY, ASSIGNOR TO GULBENKIAN SEAM-LESS RUG COMPANY, OF NEW BRUNSWICK, NEW JERSEY, A CORPORATION OF NEW JERSEY.

BRAKE FOR PILE-WIRE-CONTROLLING MECHANISM FOR LOOMS.

Application filed August 3, 1926. Serial No. 126,899.

My invention relates to pile wire controlling mechanism for looms and more particularly to the rope motion thereof, by means of which the pile wires are inserted into the 5 open warp shed of the fabric being woven.

In looms employing pile wires, by means of which the cut pile fabric is produced, the pile wires are successively drawn from the woven fabric by means of a continuously 10 driven chain operatively connected to a suitable reciprocating carriage. The carriage is provided with mechanism adapted to engage the chain, and to be released from the chain when the pile wire is entirely withdrawn 15 from the fabric. The carriage is also provided with mechanism adapted to operatively engage the head of each of the pile wires.

For inserting the withdrawn pile wire into the open warp shed a rope motion is employed, having a rope connected at one of its ends to the carriage and its opposite end connected to a spirally grooved rope wheel. The rope wheel is secured to a shaft to which power is intermittently applied and 25 released, the power being applied when it is desired to insert a pile wire and by means of which the rope wheel is revolved, subsequently winding the rope on the grooved face thereof. When the pile wire is inserted 30 completely, power is released from the rope wheel which normally runs free while the wire carriage is engaged by the withdrawing chain to withdraw another pile wire from the fabric.

35 Due to the fact that the rope wheel runs free to permit the rope to be unwound therefrom when the carriage is moving outward, the rope wheel gains considerable rotational momentum, and therefore a considerable 40 amount of slack is developed in the rope. In order to reinser the pile wire, it is necessary to first take up the slack in the rope. It is to be understood that power is applied to the rope wheel for a certain definite length 45 of time in order to insert the withdrawn wire. The amount of slack developed in the rope varies considerably, therefore, there are times when the wire is not fully inserted into the fabric, and there are other times when 50 the power is not released when the wire is fully inserted, due to the variation in the

amount of slack in the inserting rope. These conditions many times cause stoppages of the loom, and breakage of the elements of the loom as are well known to those familiar 55 with the art.

The object of my invention is to prevent the running of slack in the inserting rope. The details of my invention will be more fully disclosed hereinafter, reference being 60 had to the accompanying drawings, of which:

Fig. 1 is a front elevation of sufficient of 65 the elements of a loom to thoroughly illustrate my invention;

Fig. 2 is a transverse sectional elevation taken along the line 2—2 of Fig. 1;

Fig. 3 is a sectional elevation taken along the line 3—3 of Fig. 2.

Referring to Fig. 1, the wire controlling 70 carriage is illustrated at 1 and is adapted to be reciprocated upon a rail 2 suitably secured to the frame of the loom. The carriage 1 is moved outward in the direction of the arrow A by means of a continuously 75 driven chain 3 to which motion is applied by means of a continuously driven sprocket 4. The carriage 1 is provided with mechanism whereby the said carriage is operatively connected to the chain 3, and a latch 80 5 on the carriage 1 is adapted to engage a projection 6 on the rail 2, by means of which the carriage is released from the chain when it reaches the outer end of its withdrawing motion.

85 A bracket 7 is formed on the carriage 1 for the reception of one end of a rope 8 which is suitably secured therein. The rope 8 passes around an idler pulley 9 rotatably mounted on the frame of the loom and thence around the grooved face 10 of a spiral rope wheel 11, one end of said rope 90 being secured to the wheel 11 at a point 12.

The rope wheel 11 is secured to one end 95 of a shaft 13, which is rotatably mounted in a bearing 14 adjacent the rope wheel 11, and in a sleeve 15 which is rotatably mounted in a bearing 16 on the frame of the loom adjacent the opposite end of the shaft 13. The sleeve 15 is provided at one end 100 with a bevelled pinion 17, and at the opposite end with one element 18^a of a friction

clutch 18. The second element 18^b of the friction clutch 18 has a hub 20 splined to the shaft 13.

Suitable mechanism is provided for causing operative engagement of the elements 18^a and 18^b of the clutch 18 in timed relation with the other co-operating elements of the loom, it being understood that the bevelled gear 17, the sleeve 15 and the flanged element 18^a of the clutch 18 are continuously driven from a suitable source of power. The above described mechanism is common to looms on which seamless rugs are woven, and forms no part of the present invention, my invention comprising mechanism applied to the shaft 13 to prevent the development of excessive rotational momentum as above described.

For attaining the object above referred to, I provide a ratchet wheel 25 having a hub 26 loosely mounted on the shaft 13 adjacent the inner end of the bearing 14. The hub 26 is provided with a planed or finished periphery 27 which is surrounded and engaged by a permanently set brake 28. The brake 28 comprises a split band comprising two semi-circular shoes 29 and 30, each having an ear 31 mounted on a pivot pin 32, which is secured in a lug 33 formed on the flange 35 of a collar 36, secured by means of a set screw 37 to the shaft 13. Friction material 38 is secured to each of the shoes 29 and 30 of the brake 28, between said shoes and the plane surface 27 of the hub 26, of the ratchet wheel 25. Each of the shoes 29 and 30 is provided with lugs 39 and 40 respectively, and a bolt 41 passes through apertures formed in said lugs and extends beyond the lug 40 in the present instance. The head 42 of the bolt 41 engages the outer side of the lug 39 and a nut 43 is adapted to the opposite threaded end 44 of the bolt 41. Intermediate the lug 40 and the nut 43, a compression spring 45 is mounted, by means of which and the nut 43 any desired amount of pressure may be applied by the brake shoes 29 and 30 to the hub 26 of the ratchet wheel 25.

A pawl 46 is pivoted to the frame of the loom at 47, and is adapted to engage the teeth of the ratchet wheel 25. When power is applied to the shaft 13 for the purpose of winding the rope 8 on the wheel 11, which is rotated in the direction of the arrow C, Fig. 3, the brake mechanism 28 and the ratchet wheel 25 rotate with the shaft 13, the pawl 46 merely riding over the face of the teeth of the ratchet wheel 25. This occurs when the elements 18^a and 18^b of the clutch 18 are in operative engagement with each other, and the carriage 1 is moving in the direction of the arrow B, Fig. 1, to insert a pile wire into the open warp shed of the fabric being woven.

When the wire is completely inserted, the

elements 18^a and 18^b of the clutch 18 are disengaged and the chain 3 is then operatively connected to the carriage 1 to move said carriage in the direction of the arrow A, Fig. 1. The shaft 13, at such time, is rotated in an opposite direction, indicated by the arrow D in Fig. 3, by means of the rope 8 and the wheel 11. Rotation of the shaft 13 in this direction is opposed by means of the pawl 46 operatively engaging the teeth of the ratchet wheel 25, thereby stopping the rotation of said wheel and the hub 26 thereof, the collar 36 being secured to the shaft 13 obviously rotates with said shaft and carries with it the brake 28 thereby developing an opposing braking force between the brake elements 29—30, and the hub 26 of the ratchet wheel 25. Such operation prevents the development of excessive rotational momentum by the wheel 11 and shaft 13, and subsequently prevents slack from running in the rope 8 when the carriage 1 is released from the chain 3. The absence of slack in the rope 8 makes the operating length of said rope substantially constant, therefore, the action of the clutch 18 may be more accurately adjusted to release the carriage 1 at the proper time after a wire is completely inserted in the warp shed of the fabric being woven.

Having described one embodiment of my invention, various modifications will obviously present themselves to those familiar with the art, therefore, only such limitations should be placed upon the scope of my invention as are prescribed by the appended claims or dictated by the prior art of record.

I claim:

1. In pile wire controlling mechanism for looms having a reciprocating carriage, a rope motion for moving said carriage inward with respect to said loom, and means for moving said carriage outward with respect to said loom, said rope motion including a shaft adapted to be rotated in a direction to move said carriage inward, and to rotate freely in a reverse direction when the carriage moves outward, means operable by the reverse movements of said shaft, adapted to oppose the rotation of said shaft when the carriage is moving outward and to permit rotation of said shaft free of the said opposition when the carriage is moving inward.

2. In pile wire controlling mechanism for looms having a reciprocating carriage, a rope motion for moving said carriage inward with respect to said loom, and means for moving said carriage outward with respect to said loom, said rope motion including a shaft adapted to be rotated in a direction to move said carriage inward, and to rotate freely in a reverse direction when the carriage moves outward, a brake mechanism operable by the reverse movements of

said shaft, adapted to oppose the rotation of said shaft when the carriage is moving outward and to permit rotation of said shaft free of the said opposition when the carriage is moving inward.

3. In pile wire controlling mechanism for looms having a reciprocating carriage, a rope motion for moving said carriage inward with respect to said loom, and means for moving said carriage outward with respect to said loom, said rope motion including a shaft adapted to be rotated in a direction to move said carriage inward, and to rotate freely in a reverse direction when the carriage moves outward, means operable by the reverse movements of said shaft, adapted to oppose the rotation of said shaft when the carriage is moving outward and to permit rotation of said shaft free of the said opposition when the carriage is moving inward comprising a brake drum carried by and adapted to rotate with said shaft when the carriage moves inward, a brake shoe carried by said shaft and adapted to frictionally engage said brake drum, and means carried by a relatively fixed portion of said loom for opposing rotation of said brake drum when the carriage is moving outward.
4. In pile wire controlling mechanism for looms having a reciprocating carriage, a rope motion for moving said carriage inward with respect to said loom, and means for moving said carriage outward with respect to said loom, said rope motion including a shaft adapted to be rotated in a direction to move said carriage inward, and to rotate freely in a reverse direction when the carriage moves outward, means operable by the reverse movements of said shaft, adapted to oppose the rotation of said shaft when the

carriage is moving outward and to permit rotation of said shaft free of the said opposition when the carriage is moving inward comprising a ratchet wheel loosely mounted on said shaft, a hub on said ratchet wheel, a brake secured to said shaft and engaging said hub, and a pawl pivoted on the frame of the loom adapted to engage the teeth of said ratchet wheel and prevent the rotation thereof when the carriage moves outward and to ride over the teeth of said ratchet wheel when the carriage moves inward.

5. In pile wire controlling mechanism for looms having a reciprocating carriage, a rope motion for moving said carriage inward with respect to said loom, and means for moving said carriage outward with respect to said loom, said rope motion including a shaft adapted to be rotated in a direction to move said carriage inward, and to rotate freely in a reverse direction when the carriage moves outward, means operable by the reverse movements of said shaft, adapted to oppose the rotation of said shaft when the carriage is moving outward and to permit rotation of said shaft free of the said opposition when the carriage is moving inward comprising a ratchet wheel loosely mounted on said shaft, a hub on said ratchet wheel, a brake secured to said shaft comprising shoes engaging the periphery of said hub, means for regulating the frictional bearing of the shoes on said hub, and a pawl pivoted on the frame of the machine adapted to engage the teeth and prevent rotation of said ratchet wheel when the carriage is moving outward and to ride over the teeth of said ratchet wheel when the carriage moves inward.

WILLIAM E. SMITH.
